UNITED STATES PATENT OFFICE.

BUEL COUCH, OF SIOUX CITY, IOWA.

LOOSE-LEAF BINDER.

Application filed June 10, 1926. Serial No. 114,948.

My invention relates to loose leaf binders, and it is my object to provide such a binder in which the split rings are locked together without the use of a spring element.

More particularly, my invention embodies a binder including a pair of ribs hinged together, a crank rod journaled relative to one of the ribs, and elements secured to the other rib and coacting with the crank rod in such a way that rotation of the crank rod will produce positive hinging movement between the ribs from a locked position to an open position, and vice versa.

A further object of my invention is to provide such a structure which is a very simple, durable and inexpensive construction.

Another object of the present invention is to provide such a binder in which the rings are locked in closed position by the engagement of the crank rod with one of its coacting members, in such a way that the coacting throw of the crank rod has moved past dead center relative to said member and the crank handle of the crank rod has engaged one of the ribs of the binder to prevent further movement of the throw beyond said past-dead-center position.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Fig. 1 is a plan view of the binder in closed position, a portion of a book back being shown attached thereto.

Fig. 2 is a similar view of the binder in open position.

Fig. 3 is an end view of the binder itself.

Fig. 4 is a transverse sectional view, taken on the line 4—4 of Fig. 1.

Fig. 5 is a transverse sectional view, taken on the line 5—5 of Fig. 1.

Fig. 6 is a transverse sectional view, taken on the line 6—6 of Fig. 2.

Fig. 7 is a transverse sectional view, taken on the line 7—7 of Fig. 2.

Fig. 8 is a plan view of a portion of the binder illustrating a modified form of the means for connecting the rings to the binder.

Fig. 9 is a transverse sectional view of the same, taken on the line 9—9 of Fig. 8.

I have used the reference character 10 to indicate generally the leather, composition

or fabric covering of a loose leaf book. The binder for the book comprises a pair of angle-shaped ribs, 11 and 12, which are hinged together by means of hinges, 13, and secured to the covering, 10, as by means of lacing or clips, 14, extending through openings, 15, in the binder and through the covering.

The leaf-receiving ring elements, 16 and 17, are secured to the ribs, 11 and 12, respectively, by threading into any of several tapped openings, 18, in the respective ribs. Thus the rings may be adjusted longitudinally of the binder to fit varying sizes of loose leaves.

In most types of binders a spring is used to maintain the two halves of the binder in position, in which the rings will be closed and locked against each other. I provide means eliminating the necessity of springs and in which it is not necessary to grasp the rings themselves to open them. This comprises a crank rod, 19, journaled in lips, 20, projecting upwardly from the rib, 11, and having the crank throws, 21 and 22. The crank throws, 21 and 22, extend approximately in the same direction radially from the axis of the crank rod. An arm, 23, is secured to the rib, 12, and extends over the throw, 22. Arms, 24, are secured to the rib, 12, and extend under the throws, 21, and when the binder is in closed position, are locked against the rib, 11, by the engagement of the throws, 21.

A crank arm, 25, is provided at one end of the crank rod, 19, and is so positioned relative to the throws, 21 and 22, that when it engages one of the ribs, in the position shown in Fig. 1, the throws, 21, will have passed slightly beyond dead center relative to the elements, 24, and will engage said elements with sufficient pressure to prevent the crank rod accidentally rotating to position to allow the binder to open.

It will be understood that the resiliency of the crank rod itself will allow the throws, 21, to pass dead center under pressure.

The crank arm, 25, has a portion, 26, bent downwardly to engage the rib, 11, and this downwardly hooked portion allows a greater range of movement of the crank arm toward the open position shown in Fig. 2 by accommodating the flange of the rib, 11.

Figs. 3, 4 and 5 show the various portions of the crank arm in the closed position illustrated in Fig. 1. Fig. 4 illustrates how the throw, 22, has been rotated to position to

allow the element, 23, to move toward the rib, 11. Fig. 5 illustrates how the throw, 21, has passed dead center to lock the element, 24, against the rib, 11.

5 Fig. 6 illustrates how the throw, 22, has rotated to position to open the rings, and Fig. 7 illustrates how the throw, 21, has rotated to position to allow such opening by moving away from the element, 24.

10 In Figs. 8 and 9 I have shown a modified means of connecting the rings to their respective ribs. The rib, 12^a, is formed without a flange, and is provided with a series of slots, 12^b, in each of its edges. The ring, 12^c, has a U-shaped portion, 12^d, the arms of which are received in opposite ones of the slots, 12^b, and which embraces the rib, as shown in Fig. 9. A locking clip, 12^e, coacts with slots, 12^f, in the portion, 12^d, to maintain the ring in attachment with the rib.

Some changes may be made in the construction and arrangement of the parts of my invention without departing from the real spirit and purpose of my invention, and it is my intention to cover by my claims, any modified forms of structure or use of mechanical equivalents which may be reasonably included within their scope.

25 30 I claim as my invention:

1. In a loose leaf binder, a pair of ribs hinged together, a crank rod journaled over one of the ribs, and having throws, and members secured to the other rib, extending 35 above and below said throws.

2. In a loose leaf binder, a pair of ribs hinged together, a crank rod journaled on one rib, a member secured to the other rib and extending under a throw of the crank rod, said throw being adapted to force the 40 said member against the rib under the crank rod, and a crank handle adapted to engage one of the ribs, in position allowing said throw to pass dead-center relative to its coacting member and to thereby lock the ribs 45 against hinging movement.

3. In a loose leaf binder, a pair of ribs hinged together, a crank rod journaled on one rib, a member secured to the other rib and extending under a throw of the crank 50 rod, said throw being adapted to force the said member against the rib under the crank rod, a crank handle adapted to engage one of the ribs in position allowing said throw to pass dead center relative to its coacting 55 member and to thereby lock the ribs against hinging movement, and means coacting with the crank rod to cause the ribs to hinge away from said locked position.

4. In a loose leaf binder, a pair of ribs hinged together, lips projecting from one 60 of said ribs, a crank rod journaled in said lips, and members secured to the other rib, projecting above and below throws of said 65 crank rod.

Signed at Sioux City, in the county of Woodbury and State of Iowa, this 5th day of June, 1926.

BUEL COUCH.
